UNITED STATES PATENT OFFICE.

SAMUEL A. ADAMS AND JORDAN LEICESTER, OF MERRY HILL, NORTH CAROLINA.

FLOWER STAND.

Application filed September 3, 1924. Serial No. 735,608.

To all whom it may concern:

Be it known that we, SAMUEL A. ADAMS and JORDAN LEICESTER, citizens of the United States, residing at Merry Hill, in the county of Bertie and State of North Carolina, have invented certain new and useful Improvements in Flower Stands, of which the following is a specification.

This invention relates to stands and more particularly to stands for supporting flower pots and the like. It is desirable that stands for this purpose be more or less ornamental in appearance and yet, they must be inexpensive to manufacture in view of the use to which they are put and, furthermore, in view of the fact that they are ordinarily more or less exposed to the elements if arranged upon porches or verandas. Therefore, the present invention has as one of its objects to provide a flower stand which may be manufactured in large quantities from inexpensive material and, therefore, sold at a low price and which will, at the same time, be ornamental and attractive in appearance.

Another object of the invention is to provide a stand consisting of a minimum number of parts so constructed and assembled as to render the stand exceptionally substantial and capable of sustaining considerable weight with regard to its size.

A further object of the invention is to provide a stand so constructed that its component parts may be assembled with maximum ease and in an expeditious manner, so that the various parts having been milled to the required form, the same may be quickly assembled and the article completed in a minimum period of time.

In the accompanying drawings:

Figure 1 is a view partly in elevation and partly in vertical transverse section, illustrating a stand constructed in accordance with the present invention.

Figure 2 is a horizontal sectional view taken substantially on the line 2—2 of Figure 1, looking in the direction indicated by the arrows.

Briefly stated, the stand embodying the invention comprises a top which is indicated in general by the numeral 1, legs which are indicated in general by the numeral 2, a core block indicated by the numeral 3, and bracing members indicated by the numeral 4.

Each of the legs 2 of the stand comprises a substantially vertically extending upper portion 5, a downwardly and outwardly ex-

tending intermediate portion 6, and a preferably downwardly and slightly inwardly curved lower or foot portion 7, the legs being made from wood and turned to the required shape. As stated, the upper portions 5 of the legs extend substantially vertically, and this is particularly true of the inwardly presented faces 8 of the said portions 5, and in assembling the upper portions of the legs with the center or core block 3, the said faces 8 of the upper portions of the legs are disposed flat against the four side faces of the block and secured thereto by nails or other suitable fastening elements 9, driven through the portions 5 of the legs and into the said block. It will be observed by reference to Figures 1 and 2 of the drawings, that the center or core block 3 is of rectangular form and is preferably made of wood, the block being preferably of greater height than width and the side faces of the block being preferably of a width greater than the transverse thickness of the upper portions 5 of the legs 2, the said portions of the legs being symmetrically arranged with relation to the respective faces of the block. In thus assembling and securing together the block 3 and the upper portions of the legs 2, the upper ends of the said portions of the legs and the upper end of the block are brought into exact registration and, therefore, combined, form a substantially cruciform flat supporting surface upon which the intermediate or central portion of the top 1 is designed to rest, as clearly shown in Figure 1 of the drawings, and thus be firmly supported.

Having assembled and secured together the core block and legs, the next step in completing the structure is to dispose the assemblage in centered position upon the under side of the top 1, whereupon nails or other suitable fastening elements 10 are driven diagonally through the upper ends of the portions 5 of the legs and into the under side of the said top without, however, piercing the upper surface of the top and without passing through the upper end of the core block.

To render the structure more substantial and durable, and capable of supporting considerable weight, the bracing or bracket members 4 are provided and these members may be of any desired design and more or less ornamental, and each comprises a vertical lower end face 11 and a horizontal

upper end face 12. In assembling the bracing members 4 with the structure assembled as so far described, each bracing member is disposed against a respective leg 2 at the outer face of the upper portion 5 thereof with its flat end face 11 resting flat against the said outer face of the said portion of the leg, and a nail or other suitable securing element 13 is driven through 10 the lower end portion of the bracing member, through the said upper portion 5 of the leg, and into the corresponding face of the center or core block 3. The member 4 is at such time so disposed that its face 12 will engage flat against the under side of the top 1, and a nail or other suitable securing element 14 is driven through the upper end portion of said member 4 and diagonally into the under side of the said top 1, without, however, piercing the upper side of the top.

In this manner, the structure is completed and it will be evident by reference to Figure 1, that the structure is exceptionally substantial and durable. It will also be evident that inasmuch as the fastening elements 10 and 14 are driven diagonally into the top 1, the top is more securely united to the supporting under structure than would otherwise be the case and there is less likelihood of splitting of the top. It will furthermore be evident that inasmuch as the securing elements 13 are driven not only through the bracing members 4 and the upper portions 5 of the legs 2, but also into the center or core block 3, the legs 2 are additionally secured to the said core block but without the employment of additional securing elements. It will also be observed that the center or core block 3 serves not only to suitably space the upper portions of the legs, but, furthermore, it, in combination with the upper ends of the said legs, constitutes a very firm bearing surface for the central portion of the top 1.

Having thus described the invention, what I claim is:

1. A stand of the class described comprising a core block having a flat upper end and flat side faces, legs having the inner faces of their upper portions disposed against the respective side faces of the core block, fasten-

ing elements secured through the said upper portions of the legs and into the core block, the upper ends of the legs occupying the same plane as the upper end of the core block, a top disposed centrally of its under side upon the upper end of the core block and the upper ends of the legs, fastening elements secured through the upper end portions of the legs and into the under side of the said top, brace members having lower end faces disposed against the outer faces of respective ones of the said legs at the said upper portions of the legs and upper end faces disposed against the under side of the said top, fastening elements secured through the lower end portions of the brace members, the upper end portions of the respective legs, and into the said core block, and other fastening elements secured to the upper end portions of the said brace members and into the said top.

2. A stand of the class described comprising a core block having a flat upper end and flat side faces, legs having the inner faces of their upper portions disposed against respective side faces of the core block, fastening elements secured through the said upper portions of the legs and into the core block, the upper ends of the legs occupying the same plane as the upper end of the core block, a top disposed centrally of its under side upon the upper end of the core block and the upper ends of the legs, fastening elements secured diagonally through the upper end portions of the legs and into the under side of the said top, brace members arranged each between a respective one of the legs and the said top and having a lower end face disposed against the outer face of the upper portion of the respective leg and an upper end face disposed against the under side of the said top, fastening elements secured through the lower end portions of the said brace members, the upper portions of the respective legs, and into the core block, and other fastening elements secured diagonally through the upper end portions of the said brace members and into said top.

In testimony whereof we affix our signatures.

SAMUEL A. ADAMS. [L. S.]
JORDAN LEICESTER. [L. S.]
